UNITED STATES PATENT OFFICE.

JOHN WOLF, OF LAPORTE, INDIANA, ASSIGNEE, BY KIRSHNE ASSIGNMENTS, TO ADVANCE-RUMELY COMPANY, OF LAPORTE, INDIANA, A CORPORATION OF INDIANA.

PLOW-LIFT.

1,206,491.

Specification of Letters Patent. Patented Nov. 28, 1916.

Application filed March 28, 1915. Serial No. 17,086.

To all whom it may concern:

Be it known that I, JOHN WOLF, a citizen of the United States, residing at Laporte, in the county of Laporte and State of Indiana, have invented a certain new and useful Improvement in Plow-Lifts, of which the following is a specification.

My invention relates to improvements in plowing engines and has for one object to provide a new and improved connection between the plowing engines and the plows carried thereby.

Another object is to provide an easy and convenient adjustment of the relation between the plows and the engines, the depth to which the plows plow and means for transmitting a reversing movement from the engine to the plows.

Other objects will appear from time to time in the specification.

Figure 1 is a side elevation; Fig. 2 is a detailed rear view showing parts omitted and parts in section; Fig. 3 is a vertical section through the traction bar; and Fig. 4 is a detailed side elevation of the adjusting mechanism.

Like parts are indicated by like letters throughout the several figures.

A is the engine frame.

A¹ a drive wheel, A² a forward steering wheel and A³ the driver's seat.

I have not illustrated the engine transmitting and accompanying mechanism because they form no part of my invention.

B, B¹ are A-frames downwardly projecting from the engine frame A adjacent the rear end thereof on either side of the traction or driving wheel. They serve as guides to assist in the positioning of the plows and also to steady the plows and take the load from the tension links when the engine is reversed with the plows in the ground as is the case sometimes.

B², B³ are tension links pivoted at their forward ends on the frame A, and at their rear lower ends on the rigid traction beam B⁴. This traction beam is built up as indicated of an angle bar B⁵ and a plate B⁶, this plate and angle bar being slightly shorter than the frames B, B¹. The pins B⁷, B⁸ are rigidly attached to the angle bar and plate and project outwardly past the A-frames B, B¹, being ordinarily in working engagement with them.

C is a rock shaft journaled in the frame

A. It has at either end a rock arm C¹ to which is pivoted a link C². The link C² supports each one of the pins from the opposed end of the traction bar. It will be noted that by means of a series of holes the pivotal point of the link C² on the rocker arm C¹ may be varied.

C³ is an operating lever adjustably mounted on the shaft C by means of the toothed connection C⁴ and held in position by the pins C⁵ as indicated.

C⁶ is a quadrant toothed at C⁷ to engage the latch C⁸ controlled by the thumb piece C⁹ on the end of the lever.

The plows or plow as the case may be are or is attached to and drawn from the traction bar by the link D which may be positioned by the pin D¹ engaging any one of the holes D².

The plow beams D³, D⁴ and plows D⁴, D⁵ are diagrammatically shown as indicated.

It will be evident that while I have shown in my drawings an operative device still many changes might be made both in size, shape and arrangement of parts without departing from the spirit of my invention and I wish, therefore, that my drawings be regarded as in a sense diagrammatic.

The use and operation of my invention are as follows: The tractor is a fixed weight. If the ground is soft it sinks in, if hard it rides on the surface. The depth which the operator wishes to have the plows penetrate is fixed and does not vary. If the forward end of the plow beams are fixed in height with respect to the tractor the plows will cut deep when the engine is down and shallow when the engine is up. Experience shows that it is desirable to have the depth of the furrow independent of the depth to which the traction engine sinks. Under ordinary circumstances the general ground conditions under which the engine operates are fixed and previously known, but there are bound to be slight variations as the furrow is being made, in other words, the operator always knows whether he is going to be plowing a mud field or virgin sod, but there are bound to be variations in either field. It is these variations from time to time during operation, which the adjusting lever takes care of. The variations, however, caused by altogether different conditions, the operator cares for by varying the connection between the adjust-

ing lever and the plow beam, and he makes such adjustment that under ordinary circumstances the proper position of the lever will be the central position, though sometimes the plow must be raised or lifted during the operation to combat the local variations. Under ordinary circumstances with the plow lever at the central position as indicated the plows will take the proper depth, if he wishes them to throw them down deeper he pushes forward on the lever and this operating through the rocker arm thrusts the beam down and causes the plow to bite deep. If he wishes to decrease 10 the depth he pushes the other way.

The A-frame arrangement stiffens and positions the plow and the built-up traction beam. This traction beam moves up and down and it is through its movement that 20 the height of the plow beams is varied. It has sufficient play so when the engine backs up with the plows in the ground the A-frames take the load and the long flexible links B², B³ will not be bent by compressor.

25 I claim:

1. The combination with a traction engine of a draw bar, means for transmitting the pull from the engine to the bar, separate means for raising and lowering the bar with 30 respect to the engine frame and means for guiding the draw bar comprising an A frame mounted on and downwardly depending from the engine frame and located immediately in front of and in loose engagement with the draw bar.

2. The combination with a traction engine of a draw bar, means for transmitting the pull from the engine to the bar, separate means for raising and lowering the bar 40 with respect to the engine frame and means for guiding the draw bar comprising an A frame mounted on and downwardly depending from the engine frame and located immediately in front of and in loose engagement with the draw bar, the side of 45 the A frame in engagement with the draw bar being substantially perpendicular to the link.

3. A draw bar for traction engines and

the like comprising an angle bar and a flat 50 plate separated one from the other, traction pins held between the bar and the plate and projecting beyond the ends thereof, the bar and one flange of the plate being perforated in register one with the other, traction 55 links pivoted at one end of the engine frame and at the other on the traction pins, and means for supporting the draw bar from the engine frame.

4. The combination with a traction engine frame of a draw bar, a pivoted traction connection between the bar and the frame, means for adjustably supporting the bar on the frame and for raising and lowering it with respect to the frame, said 60 means comprising a bell crank, a controlling lever and a link connection between the bell crank and the draw bar, means for varying the effective length of the connecting link to vary the response of the draw bar to the 65 manipulation of the end lever.

5. The combination with a traction engine frame of a draw-bar, a pivoted traction connection between the bar and frame, operator controlled means for raising and lowering the bar with respect to the frame 70 during operation, together with means adjustable only when the machine is not in operation for varying the response of the draw-bar to the operator controlled means. 75

6. The combination with a wheeled plow frame of a draw bar, a pivot tension connection between the frame and the bar, a manual control, means and a connection between such manual control means and the bar 80 whereby the operator may raise and lower the bar, releasable means for locking such bar in position, and means independent of such manual control for varying the relation between the manual control and the 85 draw bar.

In testimony whereof, I affix my signature in the presence of two witnesses this 22nd day of March 1915.

JOHN WOLF.
